CLAIM

The ornamental design for a combined wet and dry vacuum cleaner, as shown and described.

DESCRIPTION

FIG. 1 is a front perspective view taken from the right of a combined wet and dry vacuum cleaner showing our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a plan view thereof; and,

FIG. 7 is a bottom view thereof.

The dashed lines are illustrative purposes only and form no part of the claimed design.

FIG. 1

FIG. 2

FIG. 3

FIG. 4

FIG. 5

FIG. 6

FIG. 7
